D. BRITTAIR

BLOTTER ATTACHMENT FOR PEN STAFFS

Filed Feb. 18, 1925

Patented Apr. 6, 1926.

1,579,465

UNITED STATES PATENT OFFICE.

DOSS BRITTAI, OF GALESBURG, ILLINOIS.

BLOTTER ATTACHMENT FOR PEN STAFFS.

Application filed February 18, 1925. Serial No. 10,092.

To all whom it may concern:

Be it known that I, DOSS BRITTAI, a citizen of the United States, and resident of Galesburg; in the county of Knox and State of Illinois, have invented certain new and useful Improvements in Blotter Attachments for Pen Staffs, of which the following is a specification.

My invention is an improvement in blotter attachments for pen staffs, and it consists in the combinations, constructions and arrangements herein described and claimed.

An object of the invention is the provision of a blotter attachment for pen staffs which will comprise a blotter member that can be replaced at slight cost and is efficient in use.

A further object of the invention is the provision of a blotter attachment of the character described which can be readily applied to a pen staff and which when in applied position on the pen staff will be in position for convenient use and will not interfere with the use of the pen staff in an ordinary manner or prevent the placing of the pen staff in the pocket of a garment or in like place.

Other objects and advantages of the invention will be apparent from the following description, considered in conjunction with the accompanying drawings, in which

Fig. 1 is a perspective view of one form of blotter attachment embodying the invention applied to a fountain pen,

Fig. 2 is a fragmentary vertical section along the line 2—2 of Fig. 1,

Fig. 3 is a side elevation of another form of blotter attachment embodying the invention and operatively applied,

Fig. 4 is a vertical section through a third form of blotter attachment embodying the invention in applied position on a pen staff, the latter being shown in side elevation,

Fig. 5 is a view similar to Fig. 3, showing a fourth form of blotter attachment embodying the invention,

Figs. 6 and 7 are views similar to Fig. 4 and respectively showing a fifth form of blotter attachment and a sixth form of blotter attachment, both embodying the invention,

Fig. 8 is a view similar to Fig. 5, showing a seventh form of blotter attachment embodying the invention,

Fig. 9 is a plan view of the parts shown in Fig. 8,

Fig. 10 is a side elevation of still another embodiment of the same invention, and

Fig. 11 is a fragmentary perspective view of still another embodiment of the invention.

In the drawings, I have illustrated the invention as applied to the usual cap 1 which fits on the barrel 2 of a fountain pen, as shown in Fig. 1. However, it is to be understood and as will appear from the following description that the invention is applicable to any pen staff or like elongated body and therefore the cap 1 may be considered as representing a pen staff for the purpose of disclosing the invention.

The form of the device exhibited in Fig. 1 and Fig. 2 comprises a backing or carrying plate 3 of metal or like relatively rigid material superimposed on the head of the cap 1 and secured to the latter by solder 4 or in any other suitable known manner. A sheet 5 of blotting paper or like material is superimposed on the carrying plate 3 and is attached to the latter by adhesive or in any other suitable known manner so that the sheet 5 can be stripped from the plate 3 when desired and replaced by a fresh and unused sheet 5.

The plate 3 preferably is circular in configuration and the sheet 5 preferably is of the same configuration as the plate 3 and is coextensive in area with the latter.

The form of the device exhibited in Fig. 3 comprises a sleeve 6 of blotting material fitting on the cap 1 and removably held in place thereon by the usual clasp 7, which carries the spring arm 8 for clamping the pen to the fabric of a garment, and a split spring retaining ring 9 which fits on and frictionally engages the cap 1.

The form of the device exhibited in Fig. 4 is a cap 10 of blotting material fitting on the head end portion of the cap 1. There is sufficient friction between the caps 10 and 1 to prevent accidental displacement of the cap 10 but the latter can be removed when used to permit a new and unused cap 10 to be substituted therefor.

The carrying structure of the form of the device shown in Fig. 5 comprises a tubular attaching member 11 split longitudinally from its inner and fore part of its length and made of spring material. The member 11 fits on the cap 1 and is provided at its outer end with a head 12 which may be

circular or any other desirable shape in configuration and may extend beyond the outer wall of the member 11, as shown. A lug 13 extends from the marginal edge of the head 12 in the direction opposite the tubular member and is bent slightly inward adjacent to its outer end. A spring lug 14 for cooperating with the lug 13 to engage at diametrically opposite points with a sheet 15 of any suitable material, such as cement, rough surfaced metal or the like which may be superimposed on the head 12 and which it is desired to retain in place on the head 12 to provide a carrying member to which the lower of a series of superposed sheets 16 of blotting material can be secured by adhesive 17. The use of the carrying member 15 may be required because smoothness of the outer face of the head 12 precludes the securing of the lower blotting sheet 16 direct to the head 12 by adhesive. Adhesive, also indicated at 17, is provided between each two adjacent sheets 16. The sheets 16 are stripped off and discarded in sequence and as used and the spring lug 14 can be sprung outwardly to permit the removal of the member 15 when all sheets 16 have been used and also to permit the replacement of the same or a new member 15 with a fresh supply of blotting sheets 16 secured thereto.

In the form of the device shown in Fig. 6, the tubular attaching member 11 has a head 18, the outer face of which is sufficiently rough to permit the lower of a series of superposed blotting sheets 19 to be secured directly thereto by adhesive 20. Adhesive, also indicated at 20 is disposed between and secures each two adjacent blotting sheets 19 together.

In Fig. 7, I show a superposed series of blotting sheets 21 secured together by layers 22 of adhesive between adjacent sheets and secured to a carrying member 23 by a layer of adhesive, also indicated at 22, between said carrying member and the lower sheet 21. The carrying member 23 has the lower end portion thereof reduced and threaded as indicated at 24 to screw into an internally screw threaded tubular extension 25 on the outer face of the head 26 of the hereinbefore described tubular attaching member 11.

The tubular attaching member 11 of the form of the device exhibited in Figs. 8 and 9 has a head 27 provided at opposite edges with angular retaining flanges 28 which have inwardly bent upper end portions overlying opposite lateral enlargements 29 at the lower end of a carrying member 30 on which a sheet 31 of blotting material is superimposed and is secured by adhesive or in any other suitable known manner. The head 27 and the carrying member 30 may have any desired suitable configuration and may extend at their ends beyond the outer face of tubular member 11, as shown. The

carrying member 30 may be slid between the inwardly extending upper end portions of the flanges 28 and the head 27 to and from position on the latter.

In the form of the device shown in Fig. 10, the tubular attaching member 11 has a head 32 formed with a convexly curved outer face and having a pair of opposite marginal flanges 33 formed with inwardly extending outer end portions 34 between which and the convexly curved head 32 a sheet 35 of blotting material can be slid to and from position on the head 32.

In the form of the device exhibited in Fig. 11, the pen staff is designated 36. The attachment comprises a spring clip 37 carrying an arm 38 which extends laterally of the staff and at its outer end carries a plate 39 which supports a removable sheet 40 of blotting paper or like material, as by having a pair of angular marginal flanges 39a which engage with edge portions of the blotting sheet and retain the latter against the plate 39.

The sheet of blotting material in each of the hereinbefore described forms of the device which employ a supporting plate may or may not be coextensive in area with the supporting plate and may be of any desired suitable shape. The blotting sheet may be carried at an end or at the side of the pen staff and the attachment carrying the blotting sheet may be a permanent part of the pen staff or separate from the pen staff and detachably engaged with the latter.

In each of the hereinbefore described forms of the device, the blotting member is supported in position for ready use and does not interfere with the use in the usual manner of a pen to which it is applied. Such blotting member can be replaced easily and quickly at a cost that is practically negligible.

Obviously, the invention is susceptible of embodiment in forms other than those which are exhibited in the accompanying drawings and I therefore consider as my own all such modifications and adaptations thereof as fairly fall within the scope of the appended claims.

I claim:

1. An attachment of the character described comprising a tubular attaching member adapted to fit on an end portion of a pen staff, a head at the outer end of the tubular attaching member, a pair of opposite retaining flanges on said head, said flanges having inwardly extending upper end portions, a blotting sheet, and a carrying member on which said blotting sheet is secured, said carrying member being adapted to be slid between the upper end portions of said flanges and said head to and from position on the latter.

2. In an attachment of the character described comprising a tubular attaching mem-

ber adapted to fit on an end portion of a pen staff, a head at the outer end of the tubular attaching member, said head being substantially in axial alignment with said tubular attaching member, and means on said head for releasably holding a blotting sheet superimposed on the head.

3. An attachment of the character described comprising a tubular attaching member adapted to fit on an end portion of a pen staff, a head at the outer end of the tubular attaching member, said head being substantially in axial alignment with said tubular attaching member, and a pair of spaced retaining members at the edge of said head for

releasably holding a blotting sheet superimposed on said head.

4. An attachment of the character described comprising a tubular attaching member adapted to fit on the end portion of a pen staff, a head at the outer end of the tubular attaching member, said head being substantially in axial alignment with said tubular attaching member, and a pair of opposite outwardly extending flanges on said head, said flanges having inwardly extending upper end portions adapted to retain the blotting material in superimposed position on said head. 20 25

DOSS BRITTAINE.
